FIG. 1 is a perspective view of an illuminated sign showing my new design;

FIG. 2 is a top plan view thereof;

FIG. 3 is a front elevational view thereof;

FIG. 4 is a bottom plan view thereof;

FIG. 5 is a right-end elevational view thereof;

FIG. 6 is a left-end elevational view thereof; and

FIG. 7 is a rear elevational view thereof.

The indicia is shown in broken lines in FIGS. 1 and 3 for illustrative purposes only.

I claim:

The ornamental design for an illuminated sign, as shown and described.
